UNITED STATES PATENT OFFICE.

IRA H. GILES, OF PITTSBURG, PENNSYLVANIA.

CAR-BRAKE.

SPECIFICATION forming part of Letters Patent No. 669,781, dated March 12, 1901.

Application filed August 8, 1900. Serial No. 26,297. (No model.)

To all whom it may concern:

Be it known that I, IRA H. GILES, a citizen of the United States of America, residing at Pittsburgh, in the county of Allegheny and 5 State of Pennsylvania, have invented certain new and useful Improvements in Car-Brakes, of which the following is a specification, reference being had therein to the accompanying drawings.

10 This invention relates to certain new and useful improvements in devices adapted to be attached to the trucks of freight and other railway cars, whereby the air-brakes of such cars will be automatically applied upon the 15 derailment of the car or cars.

Briefly described, the invention comprises 20 an air-cylinder which is supported from a bracket attached to the car-truck and has communication with the train-pipe, the air-cylinder having a valve arranged therein and held normally seated by a spring until such time as the car is derailed and the device is brought into engagement with one of the rails, at which time the valve is unseated to 25 permit of the escape of air and the application of the brakes.

In describing the invention in detail reference is had to the accompanying drawings, forming a part of this specification, and where- 30 in like numerals of reference indicate corresponding parts throughout the several views, in which—

Figure 1 is a side elevation of the truck, showing my improved device in position. Fig. 35 2 is an end view of a part of the truck and track with the device in position. Fig. 3 is a like view showing the wheel derailed and the device in engagement with the rail. Fig. 4 is a vertical sectional view of the air-cylinder. Fig. 5 is a detail view and a transverse sectional view of the valve and its operating post and plate. Fig. 6 is a detail perspective view of the operating-plate for the valve.

To put my invention into practice, I provide a bracket 1, which is supported by bolts 1' from the truck or in any other suitable manner and has arranged thereon and rigidly secured thereto an air-cylinder 3, having a screw-cap 4 on its top and provided in its 40 base with a concave valve-seat 5. This base is provided centrally of the valve-seat with

an air outlet or port 5', through which and through the plate of the bracket, upon which the air-cylinder rests, extends a threaded post 8, carried by a valve-operating plate 7. This 55 plate is provided on its upper face, at each corner, with a suitable buffer 10 to prevent contact of the plate with the base of the cylinder when the car is derailed. The threaded post 8 has secured thereon a convex valve 6, 60 which is held normally in engagement with the valve-seat 5 by a spring 10, engaging the upper face of the valve and the under face of the screw-cap 4. The cylinder is provided with an inlet-port 11, to which the flexible 65 hose 12 is connected, and this hose is joined by the union 14 to the train-pipe 15. Upon the car being derailed the valve-plate 7 coming into engagement with the rail of the track forces said plate upwardly, unseating the 70 valve 6 and allowing the air which is in the train-pipe to escape and making the application of the brakes. This valve-plate 7 also acts as a brake-shoe upon the upper face of the rail-tread when it engages with the same. 75

It will be noted that various changes may be made in the details of construction without departing from the general spirit of my invention.

Having thus fully described my invention, 80 what I claim as new, and desire to secure by Letters Patent, is—

1. In combination with a car having air-brakes, a bracket supported from the truck of said car, an air-cylinder supported from 85 said bracket, said cylinder having a concave valve-seat and an outlet-port in its bottom, a pipe connecting said cylinder with the train-pipe, a valve engaging the valve-seat, a spring for holding said valve normally seated, and 90 a valve-operating plate connected to the valve and provided on its upper face with buffers, as and for the purpose described.

2. In a brake of the class described, the combination with the train-pipe, of an air-cylinder having a valve-seat on its bottom and an outlet-port centrally of the valve-seat, a spring within the cylinder for holding the valve normally seated, a pipe establishing communication between the air-cylinder and 100 train-pipe, a valve-operating plate below the air-cylinder, a centrally-arranged post car-

ried by said plate for connecting the same to the valve, and buffers carried on the upper face of said plate, substantially as described.

3. In a brake of the class described, the combination with the train-pipe, of an air-cylinder provided on its bottom with a centrally-arranged valve-seat, and outlet-port, a screw-cap carried by said cylinder, a convex valve engaging the valve-seat, a coil-spring within the cylinder between the valve and the screw-cap for holding the valve normally seated, a pipe establishing communication between the air-cylinder and train-pipe, an

operating-plate suspended below the cylinder, and a threaded pin or post arranged centrally of the operating-plate and extending through the outlet-port of the cylinder, connecting the operating-plate to the valve, as and for the purpose described. 15

In testimony whereof I affix my signature 20 in the presence of two witnesses.

IRA H. GILES.
